the invention is particularly applicable to a forced convection system of refrigeration, where it is desired to provide a manner of cooling a refrigerator which differs from the natural air circulation system.

Refrigerators have previously been provided with fans by means of which cooled air may be forced into space requiring refrigeration. These former systems have usually had certain disadvantages. Most of these constructions have been provided with a fan to blow relatively warm air over a cooling coil and into the space to be refrigerated. Other constructions have embodied baffles built into the refrigerator to conduct the air a predetermined path within the body of the refrigerator.

It is an object of the present invention to provide a refrigerator construction in which the display pans or trays act as baffles for the air; these pans guiding the air forced into the refrigerator body. This arrangement is advantageous for numerous reasons. In the first place, the bottoms of the pans are directly in the cold air stream, and thus are directly cooled. This differs materially from the usual construction in which baffles are built beneath the display pans; for such baffles limit the direct contact of the cooled air with the pans. In the second place, the refrigerator is lighter, more efficient to operate, and cheaper to construct. A better and more complete circulation of cooled air is provided throughout the refrigerator with fewer parts, so that the cooling unit may maintain a more even temperature throughout the entire cabinet.

It is another object of the present invention to provide a means for withdrawing the warm air from the top of the refrigerator. The cooling means for a refrigerator is usually positioned at the top of the refrigerator, and the air cooled thereby tends to drop downwardly, causing a circulation of the warmer air upwardly. In the present system, the warm air is withdrawn from the top of the refrigerator, conducted downwardly to the cooling coils, and is forced transversely across the bottom of the box, the cold air forcing the warmer air upwardly into position to be again removed and conducted over the cooling coils again.

It is a further feature of our invention to provide a means of drawing air over the cooling coils, rather than blowing air over the same. The air blown by the fan might readily be forced between adjacent portions of the coils without actually contacting the same. By positioning the coils in

2 Claims.

(Cl. 62—102)

Our invention relates to an improvement in a forced convection system of refrigeration, wherein it is desired to provide a manner of cooling a refrigerator which differs from the natural air circulation system.

10 In the drawings forming a part of our specification:

Figure 1 is a longitudinal section through the refrigerator, illustrating the construction thereof.

Figure 2 is a diagram of the wiring of the operating fan.

Figure 3 is a sectional plan view taken on line 3—3 of Figure 1.

Our refrigerator A may be of any desired outward conformation, and is shown having a base 20, end walls 11 and 12, a top 13, and a rear wall 14. The front wall of the refrigerator, which in such a construction is provided with one or more display windows, being a common type of construction. The walls are preferably formed with outer covering members 15, and inner lining members 16, with insulation 17 of any desired type therebetween.

The rear wall 14 of the refrigerator A is shown as having a series of sliding doors 19 therein by means of which access is afforded to the interior of the upper portion of the cabinet. Two large doors 20 are shown in the rear wall 14, through which materials may be inserted into, or withdrawn from, the lower storage portion of the cabinet.

Extending from the rear wall 14 to the front wall of the cabinet, dividing the upper and lower portions of the cabinet, we provide a wire shelf 21 which, in the form shown, slopes downwardly at a gentle angle from the rear wall 14 to the front wall. A series of pans 22 are positioned on the shelf 21, arranged in spaced relation. These pans support products to be displayed or to be contained within the refrigerator, and cover the greatest portion of the area of the shelf 21. Air may flow through the spaces between the pans 22 and into the upper portion of the cabinet. Thus in addition to providing a support for the products to be displayed, the pans 22 act as baffles to guide and conduct the air in a desired manner into the upper portion of the refrigerator body.

Adjacent one end 11 of the refrigerator cabinet, 55 we provide a vertically extending duct 23 formed

by a vertical partition wall 24. This wall 24 is provided with openings 25 therethrough in the upper portion thereof, through which warm air from the upper portion of the cabinet above the pans 22 may be drawn. A cooling coil 26 is mounted within the lower portion of the duct 23, which coil is refrigerated in any suitable manner. In usual practice, a compressor unit 27, illustrated in the wiring diagram, acts to cool a cooling medium which flows through the coils 26 to refrigerate the same. The compressor unit may be located either within the lower storage portion 29 of the refrigerator beneath the level of the pans 22, or may be outside of the refrigerator cabinet. The cooling coil 26 is preferably of the direct expansion type with built-in heat exchanger; and the coil is preferably substantially larger than the blower fan to allow more uniform cooling of the air.

A fan 30 driven by a motor 31, draws air cooled by the coil 26 into the lower storage portion 29 of the refrigerator A. This construction has been found more effective than arrangements wherein the fan blows air forcefully over a cooling coil. The air leaving the fan is directed in somewhat of a straight path, and if the coil were in the path of air leaving the fan, some of the air might readily flow between the coils without touching the same. By drawing the air through the coil, the air is drawn from all directions through all parts of the coil, so that the movement of the air through any one portion of the coil is slower than it could otherwise be. Thus the air is cooled more effectively, and the entire coil, rather than a small portion of the entire coil, is used to a good advantage. If air were forced by the same fan through a coil of the size illustrated, only a portion of the coil would be used most efficiently.

The wiring diagram which can be used with the system illustrated in Figure 1 is shown in Figure 2 of the drawings. Line wires 32 and 33 supply the current for operating the refrigerator and fan. The line wire 32 is connected by conductors 34 and 35 to the compressor motor 27. The other terminal of the motor 27 is connected by conductors 36 and 37 to the thermostat 39 which is connected by connector 40 to the line wire 33, completing the circuit.

A relay coil 41 is connected in parallel with the motor 27. The line wire 32 is connected by conductors 34 and 42 to one terminal of the relay coil 41. The other terminal of the coil 41 is connected through conductors 43, 37, thermostat 39, and conductor 40 to the line wire 33, completing the circuit. Thus when the compressor motor 27 is in operation, the coil 41 is energized.

The line wire 32 is connected to a conductor 44 leading through the resistance coil 45 to conductor 46 connected to one terminal of the fan motor 31. The other terminal of the motor 31 is connected by conductor 47 to the line wire 33, completing the circuit.

The conductor 46 is connected by conductor 49 to the armature 50 of the relay coil 41; while the wire 44 is connected by the conductor 51 to a contact 52. When the coil 41 is energized, the armature 50 connects the conductor 49 with the contact 52, thus shorting out the resistance 45 and increasing the voltage to the motor 31. When the coil 41 is not energized, the circuit between the contact 52 and the armature 50 is broken, and the current to the fan must pass through the resistance 45, thus cutting down the speed of the fan motor 31.

In operation, the thermostat 39 controls the compressor motor 27. When the thermostat calls for a lower temperature within the refrigerator, the circuit is closed through the thermostat to the motor 27, starting the compressor into operation. Simultaneously, the coil 41 is energized, shorting the resistance coil 45 and closing a direct circuit to the motor 31 of the fan 30. The fan speed increases, drawing a greater amount of warm air from the top of the refrigerator down through the duct 23 and over the coil 26. This cooled air is then forced by the fan 30 into the lower portion 29 of the refrigerator. When the thermostat 39 cuts off the compressor motor 27, the circuit to the coil 41 is broken, the armature 50 drops, breaking the short circuit around the resistance 45, decreasing the speed of the fan 30.

The cooled air directly contacts the pans 22, and these pans form ducts for the upward passage of air. Because of the limited space provided for the upward passage of the cooled air, the temperature throughout the storage portion of the refrigerator body is equalized, providing a uniform temperature from end to end of the body. The warm air which naturally collects at the top of the cabinet is drawn off by the fan, and recooled by passing through the cooling coil 26.

In accordance with the patent statutes, we have described the principles of construction and operation of our forced convection system of refrigeration, and while we have endeavored to set forth the best embodiment thereof, we desire to have it understood that this is only illustrative of a means of carrying out our invention, and that obvious changes may be made within the scope of the following claims without departing from the spirit of our invention.

We claim:

1. A refrigerated display cabinet, comprising a closed chamber having display windows in its front, a fixed perforated horizontal partition dividing the chamber into elongated top and bottom portions which are open and unobstructed throughout substantially their entire adjacent lengths, display trays supported on said partition so as to close passage of air through the same except through spaces about the margins of said trays, cooling means located in the bottom portion adjacent an end thereof and having air duct communication at said end from the upper portion and to the lower portion of the cabinet chamber, and means for drawing air from the upper portion of said chamber and forcing it into the lower portion of said chamber after passing through the cooling means, whereby the cooled air will be put under substantially uniform pressure throughout the length of said lower portion, which pressure will cause the air to circulate about the display trays and to move from the lower portion uniformly to all parts of the upper portion through the spaces about said trays.

2. A refrigerated display cabinet, comprising a closed chamber having display windows in its front, a fixed horizontal partition dividing the chamber into elongated top and bottom portions which are open and unobstructed throughout substantially their entire adjacent lengths, display trays supported on said partition, said partition being formed to provide means for permitting air to circulate from the bottom portion to the top portion of the chamber, a vertical partition forming a vertical chamber across one end of both portions of the closed chamber and having openings into the upper part of the top

portion, cooling means located in the bottom portion of said end chamber, and means for moving air from said end chamber into and through the lower portion and thence into and through the upper portion and through the openings therefrom into the end chamber and back to the air moving means, whereby the cooled air will be put under substantially uniform pressure

throughout the length of said lower portion, which pressure will cause the air to circulate about the display trays and to move from the lower portion uniformly to all parts of the upper portion through the spaces about said trays.
